(57) **CLAIM**

The ornamental design for a cradle for vacuum cleaner, as shown and described.

DESCRIPTION

FIG. 1 is a front perspective view of a cradle for vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a rear perspective view thereof; and,

FIG. 9 is an enlarged front top right perspective view of portion 9 in FIG. 2.

The evenly spaced dash-dash broken lines depict portions of the cradle for vacuum cleaner that form no part of the claimed design. The dot-dot-dash broken lines surrounding portions of the claimed design that are illustrated in enlargements form no part of the claimed design.

1 Claim, 8 Drawing Sheets(56)
